UNITED STATES PATENT OFFICE.

HERMAN M. KAUL, OF CEDARBURG, WISCONSIN.

BLOW-OFF FOR BOILERS.

Application filed April 26, 1922. Serial No. 556,589.

To all whom it may concern:

Be it known that I, HERMAN M. KAUL, a citizen of the United States, and resident of Cedarburg, in the county of Ozaukee and 5 State of Wisconsin, have invented new and useful Improvements in Blow-Offs for Boilers, of which the following is a description, reference being had to the accompanying drawings, which are a part of this specification.

The invention relates to boilers and more particularly to the blow-off apparatus thereof.

As usually made, the blow-off apparatus 15 is constructed so that a manually operated blow-off valve is under the control of an attendant who is supposed to open this valve at predetermined periods to blow off the sediment in the settling tank of the blow-off 20 system for the boiler. With such a system of manual control there is an ever present danger of the attendant forgetting to open the blow-off valve when he should, and to do away with the human factor and reduce 25 to a certainty the operation of the blow-off valve at the periods desired, I have provided mechanism for automatically operating the blow-off valve at predetermined periods of time, and more particularly have 30 provided a float-operated mechanism for actuating the blow-off valve.

With the above and other objects in view, the invention consists in the construction and the several features of construction 35 hereinafter described and all equivalents.

In the drawings: Fig. 1 is a vertical sectional view through a device embodying the invention; Fig. 2 is a detail view of the timing valve.

In the drawings the numeral 3 designates 40 the usual settling tank connected by a pipe 4 with the boiler and having an outlet or blow-pipe 5 connected with a valve casing 6.

A blow-off valve 7 controls the flow from 45 the pipe 5 through the casing 6 to a pipe 8 which communicates with a drain pipe 9. The valve 7 is preferably of the conical type or needle valve and is normally held against a seat 10 by a spring 11 surrounding the 50 stem which projects into a chamber 12 in a casing 13.

Within the casing 13 is a float chamber 14, and a float 15 carried by a lever 16 is adapted to be raised by liquid introduced 55 into said chamber 14. The lever 16 oper-

ates in the float chamber 14 and its pivots 17 project into the chamber 12. One of these pivots 17 has an arm 18 mounted thereon and this arm carries a roller 19 adapted to engage with a member 20 secured to the stem of the valve 7, it being understood that the arm 18 is disposed in front of the member 20. With the construction thus far described it will be noted that raising of the float will swing the arm 18 forwardly 60 and when the roller 19 strikes the member 20 it will act to open the valve 7.

In order to produce a delayed closing of the valve, I provide an oil dash-pot mechanism associated therewith which may be of 70 any suitable construction. For the purpose of illustrating one form of such mechanism, I show an oil cylinder 21, a piston 22 working in the bore of said cylinder and having its piston rod 23 projecting into the chamber 12 and connected to the member 20, a by-pass 24 formed in the cylinder communicating with opposite ends of the bore, and a needle valve 25 regulating the flow of oil through said by-pass. A spring 26 acts to 80 move the piston 22 toward the casing 13. As the piston rod 23 and the valve 7 are both connected to the member 20, the movement of the valve 7 to a closing position under the influence of the springs 11 and 23 85 will be delayed or retarded by the slow flow of oil from the rear of the piston to the front thereof through the restricted by-pass 24 and the extent of this retardation may be regulated by the adjustment of the 90 valve 25.

In order to have the float operate on the valve 7 only at the time a predetermined amount of the liquid has been introduced in the chamber so as to exert a certain predetermined buoyant force on said float, I interpose 95 a counteracting force resisting the movement of the float until such condition has been reached and for this purpose a lever 27 is pivotally mounted at one end on the arm 18 and its free end engages a stop 28, and said 100 free end is also connected to the arm by means of a rod 29 and a spring 30. The rod 29 is secured to the lever 27 and the spring 30 is interposed between the head end of said rod and the arm 18, whereby relative swinging movement of the lever with respect to the arm is permitted. With this construction, until a certain force acts upon the float, the spring 30 will hold the arm 18 and lever 105 110

27 against relative movement, and as the lever 27 is held against movement by the stop 28 the arm will not be moved to operate the valve 7. When, however, this force is exceeded, the spring 30 will be compressed and the arm 18 will start to move forwardly, and because of this relative movement of the parts the upper free end of the lever 27 snaps free of the stop 28 and then the full buoyant force acting on the float is transmitted by the arm against the member 20, thereby quickly opening the valve 7 to its full extent. In order that the parts may be automatically reset on the return of the arm 18, the stop 28 is made in the form of a pivoted finger having a bevelled edge 31 adapted to cooperate with the bevelled edge 32 of the lever 27, a spring 33 permitting the lever 27 to raise the stop 28 on its return movement and normally holding said stop in operative position against a fixed stop-pin 34.

In order that the operation of the float upon the valve may be made to occur at predetermined intervals of time, I provide means for regulating the flow of fluid to the float tank, which means may be adjusted for different time intervals. For this purpose, in a supply pipe 35 leading into the float chamber 14 I provide a valve casing 36 with a needle valve 37 controlling the passage of liquid therethrough. This needle valve has its stem threaded so that it may be advanced or retracted from its seat 38 and carries a pointer 39 on its exposed end which cooperates with an index dial 40. The indices of this dial 40 represent the time it takes, for any given setting of the valve 37, for enough liquid to flow into the chamber 14 to operate the float, such as, for instance, periods from less than an hour to more than five hours. As soon as the float operates the valve 7, the liquid, or so much thereof as is necessary for the operation of the float in the desired time interval, is automatically drained out of the tank during the delayed return of the float by the opening of a drain valve 41 controlling the flow of liquid to the pipe 9. This drain valve has its stem connected to a weighted lever 42 pivotally mounted intermediate its ends upon a pin 43 on a bracket 44 in the float chamber 14. The weight 45 is at the upper end of the lever 42 while notches 46 and 47 are provided in the lower end of the lever. A pin 48 on the lever 16 has a lost motion connection with the lever 44 by reason of the notch 46 but when the float 15 is completing its valve-opening movement the pin 48 strikes the upper side of the notch 46 in the lever 44 and swings its weighted end forwardly, as shown in dotted lines in Fig. 1, and in doing so the valve 41 is opened to drain the tank 14. A stop 49 adjacent the notch 47 limits the swinging

movement of the lever 42 when the valve 41 is opened. On the return of the float to its inoperative position the pin 48 strikes the lower side of the notch 46 and throws the lever 42 over to its initial position, thereby closing the drain valve. To increase the flow of liquid from the tank 14, I provide the end of the pipe 9 with an ejector nozzle 50, and since the water blown off through the pipe 8 is at relatively high pressure, an ejector effect will be produced in the pipe 9 which will have a suction effect on the water in the tank 14.

I desire it to be understood that this invention is not to be limited to any specific form or arrangement of parts except in so far as such limitations are specified in the claims.

What I claim as my invention is:

1. In a boiler blow-off system, the combination, with the blow-off valve, of a float tank, a float in said tank, means for controlling the flow of liquid to and from the tank to produce periodic operation of said float, and means moved by the float on its upward movement for effecting the sudden opening of said valve independent of the rate of flow of the liquid into said tank.

2. In a boiler blow-off system, the combination, with the blow-off valve, of a float tank, a float in said tank, means for controlling the flow of liquid to and from said tank to produce periodic operation of said float, means moved by the float on its upward movement for effecting the sudden opening of said valve independent of the rate of flow of the liquid into said tank, and means for holding said valve open for a pre-determined period independent of the descent of said float.

3. In a boiler blow-off system, the combination with the blow-off valve, of a float tank, a float in said tank, means moved by the float to open said valve, means for restraining the action of said float until a predetermined buoyant pressure thereon is reached, and means for controlling the flow of liquid to and from the tank to produce periodic operation of said float.

4. In a boiler blow-off system, the combination, with the blow-off valve, of a float tank, a float in said tank, means moved by the float to operate said valve, an adjustable valve in the liquid supply to said tank, and a valve controlling the flow of liquid from the tank, said last named valve and said blow-off valve being automatically and periodically operated by the action of said float.

5. In a boiler blow-off system, the combination, with the blow-off valve, of a float tank, a float in said tank, means moved by the float to open said valve, means for retarding the closing movement of said valve, means for restraining the action of said

float until a predetermined buoyant pressure thereon is reached, and means for controlling the flow of liquid to and from the tank to produce periodic operation of said float.

5 6. In a boiler blow-off system, the combination, with the blow-off valve, of a float tank, a float in said tank, means controlling the supply of liquid to said float tank, means moved by the float to periodically

10 operate said valve, a float-operated drain valve controlling the flow of liquid from said tank, and means for accelerating the opening and closing movements of said valve beyond the normal rate of movement

15 of said float.

7. In a boiler blow-off system, the combination with the blow-off valve, of a float tank, a float in said tank, means moved by the float to operate said valve, means controlling the supply of liquid to the float tank, a drain valve controlling the flow of liquid from the tank, and a weighted lever operatively connected to said drain valve, said lever being engageable by the float and moved thereby near the ends of the travel of said float to open and close said drain valve, and said drain valve and blow-off valve being periodically operated by said float.

20 8. In a boiler blow-off system, the combination with the blow-off valve, of a float tank, a float in said tank, means including

an arm moved by said float to open said valve, a lever carried by said arm, a spring resisting relative movement between said arm and lever, a stop engageable by said lever for restraining the action of said float until a pre-determined buoyant pressure thereon is reached, and means for controlling the flow of liquid to and from the tank to produce periodic operation of the float.

25 9. In a boiler blow-off system, the combination with the blow-off valve, of a float tank, a float in said tank, means including an arm moved by said float to open said valve, a lever carried by said arm, a spring resisting relative movement between said arm and lever, a pivoted self-setting stop engageable by said lever for restraining the action of said float until a pre-determined buoyant pressure on said float is reached, and means for controlling the flow of liquid to and from the tank to produce periodic operation of the float.

30 10. In a boiler blow-off system, the combination with the blow-off valve, of a float tank, a float in said tank, means moved by the float to operate said valve, means for periodically operating said float, and means for facilitating the periodic draining of said tank including an ejector connected with said blow-off valve.

In testimony whereof, I affix my signature.
HERMAN M. KAUL.
